ROLLED GIRDER.

No. 831,755.

Specification of Letters Patent.

Patented Sept. 25, 1906.

Application filed April 12, 1902. Renewed February 1, 1906. Serial No. 298,966.

To all whom it may concern:

Be it known that we, ALWIN VIETOR, of Wiesbaden, and CARL HUSHAM, of Osnabrück, Germany, have invented new and useful Improvements in Rolled Girders and the Like, of which the following is a specification.

In rolling flat plates and flat bar-iron and, in general, in rolling those products both of whose groove-bounding lines to be turned in 10 the upper and lower rolls of a reversing-mill, or in each of the two rolls lying together in a three-high mill are substantially parallel straight lines, the rolling pressure—no matter in what thickness the iron is to be rolled—is 15 so distributed uniformly over the whole breadth of the section that by repeated passes of the bar through one and the same groove-opening, which by approach of the two rolls each time can always be made narrower without the bounding lines being 20 changed, such flat sections can be rolled. With all hitherto-known sections of multiple or single web girders, where the material is, as far as possible, so distributed that near the 25 neutral fiber there is little, and, on the other hand, near the places of the section farthest from the neutral fibers there is much, material this is not the case. On the contrary, the rolling pressure is there well distributed only 30 when the rolls are exactly adjusted corresponding to the groove. The flat plates, flat bar-iron, and the like referred to, in sections bounded by parallel substantially straight lines, are furthermore the only 35 known forms which can, in the direction of the rolling pressure, be laid or piled up on one another to any desired height, so that they cover with large contact-surfaces without interstices between each two successive 40 sections lying upon one another—that is, so that they fit together. This is also not the case with any of the high-webbed sections of 45 girders or rails at present used. If, for instance, several rails of the same section, several 50 U-irons, or several corrugated iron plates of ordinary sections of the same rolling are laid in any manner upon each other there is never obtained an absolutely-closed pile, the rolling-section surfaces of which fit together throughout the breadth of the section. In 55 constructional work, however, there are numerous cases in which it is of the greatest advantage if high webbed—and therefore, as regards full utilization of the metal, or saving

in weight, more perfect—girder-sections, on 55 the one hand, can be rolled, and, on the other hand, are capable of being piled one upon the other or one over the other in any desired number, fitting together without any interstices with large contact-surfaces and with 60 rolling pressure quite or as far as possible uniformly distributed over the breadth of the rolled section. Such new forms of girders, rails, and the like (“pile-section” girders, as they may be called) form the subject of the 65 present invention. These girders are characterized by their section-bounding lines composed of several variously running straight or partly-bent lengths, being practically alike, so that on piling up the sections 70 one upon the other or one over the other the lower surface of each upper piece covers the upper surface of the piece of like section lying below it in the breadth of the section or groove.

In the annexed drawings, Figure 1 is a 75 geometrical diagram illustrative of the invention. Fig. 2 shows in section a two-webbed rail with like sectioned plate capable of being piled. Fig. 3 shows several multiple webbed 80 girders of piled section lying one upon the other, of which the lowermost repose on its ends, while the uppermost and shortest is loaded in the middle.

The new and peculiarly-piled sections will 85 be obtained geometrically if one imagines a straight line O Q, Fig. 1, vertical to the roller-axis moved until it coincides with a parallel line Oⁿ Qⁿ in the same plane, the two points O and Q of the traveling line thus describing 90 equal lines—for example, the lines O O' O² O³ Oⁿ and Q Q' Q² Q³ Qⁿ consisting of several differently-directed straight or bent separate lengths. Every other point of the moved lines also describes a line equal to them—e.g., 95 P P' P² P³ Pⁿ.

Each of the surfaces O Oⁿ, Pⁿ P, or P Pⁿ Qⁿ Q is a section capable of being piled, as explained. Imagine the surface O Oⁿ Pⁿ P to be a rolled section, the line O O' O² O³ Oⁿ 100 turned in the upper roll, and the line P P' P² P³ Pⁿ in the lower roll, the axes of the rolls vertically cutting the straight lines O P and Oⁿ Pⁿ. It is clear from Fig. 1 that the thickness measured in the direction of the lines 105 O P and Oⁿ Pⁿ of the section at each place of the grooves is equal to the length O P or Oⁿ Pⁿ, so that it is possible to roll girders of such

sections with the same rolling pressure throughout the whole breadth of the section. Furthermore, from Fig. 1 it can be seen that (and how) girders with such sections of the same form can be piled up, fitting upon and into one another. It is only necessary to regard $O O^n P^n P$ as the section of the one girder and $P P^n Q^n Q$ as the like section of a second girder. The capability of being piled is solely dependent upon the uniformity of the upper and the lower line bounding the section, but not on equal thickness of the section everywhere. Small deviations of the upper and outer bounding-lines of the section as to their uniformity, which deviations may be caused by the rolling-mill practice, do not disturb the capability of the girders of being piled, if projections at the section are avoided.

20 Closely-fitting pile-section girders possess many important advantages. The ends of girders with such sections closely fitting together can be, for instance, pushed over one another, and so, without much space or 25 special arrangements being necessary, in the simplest manner riveted or bolted with lap-joints, or connected with butt-joints, pieces of the same section being employed as butt-strips. To construct girders of double or 30 multiple strength for building purposes from a stock of bars of a definite piled section, it is only necessary to lay two or more of the bars closely upon or over one another. Such piled girders can be made with any desired 35 number of webs. In grooving the rolls it is best to take into consideration from the first the wear to be expected of the parts most exposed to friction and to correspondingly thicken or strengthen the rolls at parts exposed to wear; but any deviation from the 40 proper form which would cause projections

at the section as well as at the rolled girder must be carefully avoided.

For railways, where it is a matter especially of cheapness of structure, together with maximum of durability, (for instance, especially in the case of portable and small branch railways,) the piled stock removes the inconvenience in having to provide for the various special sections for the rails and fish-plates for manufacture of the superstructures. The short waste lengths in the manufacture of rails can be employed to form fish-plates or saddles of great strength at the joints. Shorter lengths of the same 55 section can be used as chairs or saddle-supports.

Having now described our invention, what we claim, and desire to secure by Letters Patent, is—

1. A girder, channel-iron or the like having its upper and lower faces of identical dimensions and shape whereby a plurality of said girders may be piled one upon the other, the longitudinal edges of said girders being parallel and lying in planes parallel to the line of the pile whereby a plurality of piles may be laid side by side without intervening spaces, substantially as described.

2. A girder, channel-iron, or the like, having flanges and webs inclined to each other, the thickness of the flanges and webs being the same on lines parallel with the edge of the flanges substantially as described.

In witness whereof we have hereunto set 75 our hands in presence of two witnesses.

ALWIN VIETOR.
CARL HUSHAM.
